(57) **CLAIM**

We claim the ornamental design for a metal bodied chopper, as shown and described.

DESCRIPTION

FIG. 1 is a top perspective view of a metal bodied chopper; FIG. 2 is a first side elevational view of the metal bodied chopper of FIG. 1; FIG. 3 is a second side elevational view of the metal bodied chopper of FIG. 1; FIG. 4 is a third side elevational view of the metal bodied chopper of FIG. 1; FIG. 5 is a fourth side elevational view of the metal bodied chopper of FIG. 1; FIG. 6 is a top plan view of the metal bodied chopper of FIG. 1; and, FIG. 7 is a bottom plan view of the metal bodied chopper of FIG. 1. The broken lines shown in the drawings are for illustrative purposes only and form no part of the claimed design.
